UNITED STATES PATENT OFFICE.

JULIUS C. LANDMANN, OF EUREKA, NEVADA.

WATCH-CASE.

SPECIFICATION forming part of Letters Patent No. 357,395, dated February 8, 1887.

Application filed February 15, 1886. Serial No. 192,024. (No model.)

To all whom it may concern:

Be it known that I, JULIUS C. LANDMANN, of Eureka, Eureka county, State of Nevada, have invented an Improvement in Watches; 5 and I hereby declare the following to be a full, clear, and exact description of the same.

My invention relates to certain improvements in watches, and it is more especially designed to protect the movement of the watch 10 from injury in case of its being dropped.

It consists of an interior inclosing case for the movement, this case being of smaller diameter than the ordinary exterior case, so as to admit a spring between the two, by which 15 any accidental jar upon the exterior case will be prevented from acting violently upon the movement.

It also consists in the means of connecting a stem with the interior works.

20 Referring to the accompanying drawings for a more complete explanation of my invention, Figure 1 is a view of the watch open from the rear, so as to show the interior. Fig. 2 shows the back of the watch, with a portion of the 25 inner case broken away, showing my improvement. Fig. 3 is a view of the collar and rubber washer.

20 A is the exterior case of my watch, and B is the secondary or interior case, within which 30 the movement is to be contained. This secondary case is made of considerably smaller diameter than the interior of the outer case, and it is so held that it does not have actual contact with it by means of a spring, C, which 35 has its center secured above the top of the inner case, its ends extending outward and passing part way round, so as to press against the sides of the case.

D is the stem by which the watch is wound up, and this extends down through the center 40 of the spring and into the inner case, where it is connected with the winding mechanism in the usual or any suitable way. Around this stem is fitted a washer or collar, E, which is made to fit closely, and may be further secured 45 with an elastic gum or rubber, so as to allow the movement of the interior case within the outer one without making any opening or a loose joint at this point. By this construction 50 the movement is secure from injury by blows or falls, and the balance-staff pivots are safe from accident, because the force of the fall is broken on account of the loose movement of the inner case and the elastic spring upon 55 which the force of the blow is expended.

Having thus described my invention, what I claim as new, and desire to secure by Letters Patent, is—

An interior case containing the movement of a watch, an exterior case of larger diameter, having a spring interposed between the two, with its ends secured to the inner case, a winding stem extending through the sides of both cases, in combination with a washer through which the stem passes and an elastic 60 collar, whereby the dust is kept out and the inner case allowed to move within the outer one, substantially as herein described.

In witness whereof I have hereunto set my hand.

JULIUS C. LANDMANN.
